UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed October 2, 1919. Serial No. 328,019.

To all whom it may concern:

Be it known that I, ALFRED G. F. KUROWSKI, a citizen of the United States, formerly a citizen of Germany, residing in Brooklyn 5 Borough, in the county of Kings, city and State of New York, have invented certain new and useful Improvements in Typewriting Machines, of which the following is a specification.

10 This invention relates to typewriting machines, and is disclosed as a modification of an Underwood standard typewriting machine, adapted to handle thick packs of work-sheets and carbon sheets, or adapted 15 to facilitate the separate insertion of two sets of work-sheets, one set being insertable from either front or rear. The mechanism is thus well adapted to be used in certain bookkeeping or other record systems, in 20 which it is desired to make a plurality of entries upon separate sheets, and have identical copies thereof appear upon a single sheet, or upon a plurality of identical sheets.

For these and other purposes, the device 25 is shown as comprising a platen, a paper-table adapted to deliver a work-sheet to the bottom of the platen, in addition to a paper-table adapted to deliver a work-sheet to the rear of the platen well above its bottom, and

30 devices for facilitating the insertion of a work-sheet at the front of the platen. For the further facilitating of the insertion of work-sheets, the platen may normally bear against a front feed-roll, and be adapted to 35 be drawn rearwardly and upwardly away from said feed-roll, thus affording a space between the platen and the feed-roll, to permit a thick pack of work-sheets to be inserted, from either the front or the rear, 40 between the platen and the paper-table or feed-roll.

To facilitate the handling of work-sheets, there may be provided a feed-roll adjacent the aforesaid rear paper-table, and normally 45 bearing against the platen, but adapted to move rearwardly when the platen is drawn rearwardly, and may move more rapidly than the platen.

In order to enable a single work-sheet to 50 be inserted without need of withdrawing the platen to the extent effected by the aforesaid devices, there may be provided a finger-piece which is adapted to withdraw the

platens only far enough to enable a single work-sheet to be inserted. In order to 55 facilitate the collating of work-sheets, there may be provided, above the platen, a front paper-table, and in machines having a platen adapted to be drawn rearwardly, this front paper-table may be connected to move 60 with the moving platen, with the result that work-sheets, collated with the platen withdrawn, may be held collated when the platen is restored.

The device is usable for condensed billing, and to facilitate this may include not 65 only fingers at the front of the platen beneath the collating table, but may also include a device adapted to hold the record sheet at an upper rear paper-table. To produce a simple structure for doing this, said upper rear paper-table, which is normally 70 clear of the platen, may be so connected that it bears against the platen when the platen is withdrawn rearwardly. Thus, the mechanism 75 may include two devices adapted to hold the record sheet at the platen, one at the front, and one at the rear, while the outside sheets are being inserted.

Other features and advantages will here- 80 inafter appear.

In the accompanying drawings,

Figure 1 is a perspective view of an Underwood typewriting machine carriage, as modified to include the above-mentioned 85 features.

Figure 2 is an end view, largely a dia- 90 grammatical section, showing the relationship of many of the parts seen in Figure 1, and showing the platen withdrawn.

Figure 3 is a rear perspective view, illus- 95 trating the mounting of a paper-deflector.

Figure 4 is a similar view, illustrating the mounting of the bottom paper-table.

Figure 5 is a view similar to Figure 2, but 95 omitting many parts, and showing the platen in normal position.

Figure 6 is a rear view of the rear feed- 100 roll, seen in Figures 2 and 5, and showing the mounting thereof.

Figure 7 is a view similar to Figure 5, but 105 showing the special finger-piece actuated to partially withdraw the platen.

Figure 8 is a view similar to Figure 7, but 105 showing the parts in normal position.

Figure 9 is a front view of the front feed-

rolls seen in Figure 7, and also seen at the bottom of Figure 1.

The platen frame 10 includes end plates 11 and 12, and forms part of a carriage 13, which is adapted to be fed along, in any usual or desired manner, upon a rear rail 14 and a front rail (not shown), so that types 16 may print against the front side of a platen 17 at the level of the printing line, 10 which is indicated by wing-scales 18, herein shown as of a form illustrated in the patent to Helmond, No. 1,302,161, dated April 29, 1919. The platen is fast to an axle 19, and is journaled in swinging arms 20 and 21, 15 pivoted at 22, near the bottom of the platen, upon the end plates 11 and 12, respectively. In order to steady the platen in the platen frame 10, the axle 19 extends through curved slots 23 in the end plates 11 and 12. The 20 axle beyond the left-hand end plate 11 carries the usual line-space wheel 24, which is adapted to be rotated by the usual line-space lever and pawl (not shown), and is held against accidental displacement by the usual 25 line-space detent 25, it being found that if the detent is placed at or not far from the position it usually occupies in the Underwood machine, the platen may swing in the slots 23 unhindered by the detent, and yet 30 held by the detent against accidental turning.

In order to enable the platen to be held at the front of the platen frame, substantially at the wing-scales 18, there is provided a 35 strong rock-shaft 26, journaled in the end plates 11 and 12, and carrying rock-arms 27 and 28, which are connected by links 29 to the respective swinging arms 20 and 21. In the ordinary writing position, a pair of 40 strong springs 30, encircling the shaft 26, hold the links 29 substantially on dead center with the arms 27 and 28, thus enabling the platen to receive the severe blows of the types 16, without yielding. The links 29 are held at this position because a finger-piece 31, pivoted at 32 upon the end plate 11, has a lower extension 33, which carries a lug 34, underlying an extension 35 of the rock-arm 27, and the finger-piece 31 is prevented from being turned backwardly by 45 the spring 30, because an elbow 36 in the finger-piece, in its normal position, overlies a lug 37 fast upon the cover-plate 38 of the end plate 11.

50 In its normal position, the platen lies against front feed-rolls 39 and 40, which are resiliently supported from a shaft 41, in a manner which will be described a little later, said rolls projecting through openings 42 in a front plate or apron 43. This apron 43 is made fast by screws 44, passing through its lugs 45, and engaging a supporting plate 46, fast to a rod or bar 47, secured in the end plates 11 and 12. In the normal position 55 of the platen frame 10, the apron 43

stands in front of and just above a boss 48, forming the front end of a bottom paper-table 49, which is held fast by screws 50 to a bar 51, forming part of the carriage. When it is desired to insert a thick pack of 70 work-sheets over the bottom paper-table 49, the platen is withdrawn rearwardly by drawing the finger-piece 31 forwardly, causing its lug 34 to lift the rock-arms 27 and 28 to the Figure 2 position, in which 75 position a shallow fork 52, at the end of the extension 33, rests upon a roll or pin 53 of the rock-arm 27, thus holding the platen in position against the tension of the spring 30. The thick pack of work-sheets and carbon 80 sheets may then be thrust forward, over the paper-table 49, being guided upwardly by a bottom curve 54 of the table, and being deflected downwardly by a curved deflector 55, held fast to a lug 56, forming part of the 85 carriage, a screw 57 passing through the deflector 55 and entering the lug. As the pack of work-sheets and carbon sheets pass forwardly, they are deflected by the boss 48, so that they clear the rear end of the apron 43, 90 and are guided by said apron up in front of the platen, around which they may be pushed far enough to be adjusted upon a collating-table 58, which is made fast upon upper extensions 59 of the swinging arms 95 20 and 21. If desired, the thick pack of work-sheets and carbon sheets may be inserted from the front, down over the apron 43, and be deflected by a boss 60, which forms the rear end of the apron 43, so that they pass easily onto the paper-table 49, and may be collated as if inserted from the rear.

In addition to the paper-table 49, there is an upper rear paper-table 61, held fast to turned-over lugs 62 of a cross-piece 63 105 joining the ends 11 and 12, said table 61 adapted to guide work-sheets down to a deflector 64, which is adjacent a rear feed-roll or rolls 65. Normally, the feed-roll 65 occupies the position seen in Figure 5, in 110 which it bears against the platen, below the center thereof, and considerably above the paper-table 49, it being so positioned that the deflector 55 guides work-sheets inserted over the paper-table 49 clear of the feed-roll 65. In order to carry the feed-roll 65 clear of the 115 path of the platen as the platen moves rearwardly, at the actuation of the finger-piece 31, the feed-roll is carried upon a shaft 66, which moves upwardly and rearwardly at 120 the actuation of the finger-piece 31.

To effect this motion of the shaft 66, the shaft is fast to a pair of links 67, pivoted in the end plates 11 and 12, nearly at their top and nearly above the platen axle, and these links are each pivoted to a floating link 68 by a shouldered screw 68^a at each floating link 68. The links 68 are journaled on the platen axle 19, with the result that as the platen swings rearwardly and upwardly, 130

the links 68 carry the links 67 upwardly, swinging the shaft 66 rearwardly, from the Figure 5 position to the Figure 2 position. The feed-rolls 65 are journaled directly upon a feed-roll shaft 69, which is carried on rock-arms 70, journaled upon the shaft 66, and pressed forwardly against the platen by springs 71, coiled around the shaft. In order to prevent the feed-roll shaft 69 from being swung forwardly when the shaft 66 swings rearwardly, a collar 72 is provided for each rock-arm 70, adapted to limit the throw of its rock-arm by contact with lugs 73, suitably disposed upon the rock-arm 70 and the collar 72 to give the proper amount of lost-motion. The deflector 64 is yieldingly mounted with respect to the rock-arms 70, but moves almost as a unit therewith. For this purpose, the deflector 64 includes U-shaped lugs 74 upon its back, adapted to embrace the shaft 69, and has a turned-up lower end 75, terminating in a finger 76, which is adapted to lie behind the shaft 69, and hold the deflector upon said shaft. In order to hold the deflector 64 approximately in position, there is provided upon each rock-arm 70 a leaf-spring 77, which bears against the shaft 69, and is bent forward to bear against the end of the finger 76, thereby holding the deflector to approximately conform to the curvature of the platen.

The feed-rolls 39 and 40 are supported upon the shaft 41, suitably supported against rotation backwardly in the end plates 11 and 12. For supporting them, there are fast upon the shaft 41 two pairs of rock-arms 78, each carrying a shaft 79, which connects the rock-arms of its pair, and has journaled thereon an arm 80, to which are pivoted yokes 81, in which shafts 82 of the two sets of feed-rolls 39 and 40 are journaled. For holding the rock-arms 80 upwardly, to cause their yokes to hold the feed-rolls against the platen, there is provided around each shaft 79 a coil spring 83, of a usual form, which bears against a lug 84 upon its rock-arm 80. The shaft 41 is shown as steadied at its center by a U-frame 85, having two ends 86 embracing the bar 47. The shield 43 prevents the feed-rolls 39 and 40 from being displaced by swinging the yokes 81 too far on their pivots.

In order to steady the apron or shield 43, it may be provided with U-shaped extensions 87, at each end, adapted to embrace the shaft 41. In order to limit the throw of the rock-arms 80 by their springs 83, each rock-arm 80 is continued below its shaft 79, to form a stop-arm 88, which is adapted to strike against the shaft 41 when it reaches the limit of its proper throw when the platen 17 is drawn rearwardly.

When it is desired to insert a work-sheet past the feed-rolls 39 and 40, instead of actu-

ating the finger-piece 31, to withdraw the platen its full distance, the platen may be withdrawn by a finger-piece 89 a short distance and detained in this withdrawn position, thus avoiding any need for casting-off 70 mechanism for the feed-rolls 39 and 40. For this purpose, the finger-piece 89 is fast upon a short shaft 90, journaled in a bracket 91, fast upon the end plate 12, and carrying a rock-arm 92, connected by a link 93 to a bell-crank 94, pivoted at 95 upon the end plate 12, and having a pin 97, which extends through an opening 98 in said plate, and underlies the right-hand linkage 29, with the result that when the finger-piece 89 is shifted 80 from its Figure 8 to its Figure 7 position, the platen is withdrawn by the raising of the link 29 to the small extent shown in Figure 7, thus opening the small space illustrated diagrammatically between the platen and 85 the feed-rolls in said Figure 7. The platen is detained in this position because the finger-piece 89 in the Figure 7 position holds the link 93 on dead center. When a work-sheet has been inserted and the platen should be 90 restored against the feed-rolls 39 and 40, the finger-piece 89 may be swung upwardly. A spring 99 assists in returning it to its normal position.

The shift or platen frame, including the 95 ends 11 and 12, is herein illustrated as carried upon a shift-rail 100, of substantially the usual form, by a roller 101 at the bottom of the shift-frame, said rail 100 forming part of a bell-crank 102, which is adapted 100 to be swung forwardly and upwardly by the usual shift-key-lever 103. The apron or shield 43 and the boss 60 thereon, being part of the shift or platen frame, rise when the shift-lever 103 is actuated. The paper table 105 49 and deflector 55 do not rise at this time, because they are part of the main carriage. This is immaterial, however, since it is customary to insert work-sheets only when the shift-frame is in its normal position. 110

For condensed billing purposes, the record sheet may be inserted over the paper-table 61 when the platen is in its nomal position or when it is withdrawn by the finger-piece 89. The record sheet is then carried forwardly and upwardly around the platen and around over the top of the platen beneath a pair of resilient fingers 104, which are adapted to bear against the platen near its ends to detain a record sheet upon it and yet allow the sheet to be advanced by the revolving of the platen when held thereagainst by the feed-roll 65, 39 and 40. Since the table 58, as described above, moves to and fro with the platen, the record sheet is held in 120 position by the fingers 104 even when the platen is withdrawn. After the record sheet has been inserted, the bill and any work-sheets and carbons to be inserted therewith are passed over the bottom paper- 130

table 49, after the platen has been withdrawn by actuation of the finger-piece 31. Withdrawal of the platen by the actuation of said finger-piece brings the platen against a lower extension 105 of the paper-table 61, with the result that the record sheet is held in position by being pinched between the extension 105 and the platen, besides being detained by the fingers 104. The finger-piece 31 may be restored to the normal position when the work-sheets have been inserted in the manner described and typing may proceed in the usual manner, the platen being advanced as usual by action of the line-space wheel, or the usual knob (not shown). When a bill has been made out and the last entry thereof is complete, it is customary to actuate the line-space lever to advance the record sheet sufficiently to separate the entries already made thereon from the entries to be made when typing upon the next bill. Then the finger-piece 31 is actuated to withdraw the platen, the typed bill and work-sheets withdrawn, and the new bill inserted and properly aligned. Then the finger-piece 31 is actuated to restore the platen and the operation proceeds as before.

Variations may be resorted to within the scope of the invention, and portions of the improvements may be used without others.

Having thus described my invention, I claim:

1. In a front-strike typewriting machine, the combination with a revoluble platen, of a substantially horizontal bottom paper-table at the rear of the platen and having its forward edge adjacent the bottom of the platen, a rear paper-table forwardly and downwardly inclined to guide work-sheets to the back of the platen and to hold the same above the bottom paper-table, a rear feed-roll to co-operate with the platen adjacent the lower edge of the inclined rear paper-table and above said bottom paper-table, and feed-rolls positioned to engage the platen at the lower front portion thereof to co-operate with the platen in feeding work-sheets extending around the latter.

2. In a front-strike typewriting machine, the combination with a revoluble platen, and a rear paper-table adapted to guide sheets downwardly, of a bottom paper-table adapted to feed sheets horizontally, feed-rolls adapted to guide upwardly at the front work-sheets fed over either paper-table, a paper-deflector at the rear paper-table, and a rear feed-roll at said deflector.

3. In a front-strike typewriting machine, the combination with a revoluble platen, and a rear paper-table adapted to guide sheets downwardly, of a bottom paper-table adapted to feed sheets horizontally, feed-rolls adapted to guide upwardly at the front work-sheets fed over either paper-table, a paper-deflector at the rear paper-table, a

rear feed-roll at said deflector, means for moving said platen upwardly and rearwardly, and means for moving said deflector and rear feed-roll out of the way of the platen. ⁷⁰

4. In a front-strike typewriting machine, the combination with a revoluble platen, and front and rear feed-rolls, of means for moving the platen rearwardly, and connections for automatically moving said rear roll at ⁷⁵ the same time.

5. In a front-strike typewriting machine, the combination with a revoluble platen, and front and rear feed-rolls, of means for moving the platen rearwardly, and connections ⁸⁰ for automatically moving said rear roll at the same time and faster than the platen to open a space between all the rolls and the platen.

6. In a front-strike typewriting machine, ⁸⁵ the combination with a platen frame having ends, of a platen journaled at said ends, rock arms comprising the journals therefor, a rock shaft carrying a second set of rock arms, links connecting both sets of rock arms, so that rocking the shaft draws the platen rearwardly in the frame, a feed roll, swinging arms on which the roll is carried, and a connection from one set of rock arms to the swinging arms, to swing the feed roll as the ⁹⁰ platen is drawn rearwardly. ⁹⁵

7. In a front-strike typewriting machine, the combination with a platen frame including a platen adapted to be shifted in said frame of a rear feed roll, a shaft across said frame, rock arms resiliently mounted on said shaft, journals for said roll in said rock arms, and means for swinging said shaft to carry the roll away from the platen when ¹⁰⁰ said platen is shifted. ¹⁰⁵

8. In a front-strike typewriting machine, the combination with a platen frame including a platen adapted to be shifted in said frame, of a rear feed roll, a shaft across said frame, rock arms resiliently mounted on said shaft, journals for said roll in said rock arms, and swinging arms pivoted in said frame and carrying said shaft to swing the roll away from the platen when said platen is shifted. ¹¹⁰

9. In a front-strike typewriting machine, the combination with a platen frame including a platen adapted to be shifted in said frame, of a rear feed roll, a shaft across said frame, rock arms resiliently mounted on said shaft, journals for said roll in said rock arms, means for swinging said shaft to carry the roll away from the platen, and a paper-deflector mounted to move to and from the platen with the roll when said platen is ¹¹⁵ shifted in said frame. ¹²⁰

10. In a front-strike typewriting machine, the combination with a platen frame including a platen adapted to be shifted in said frame, of a rear feed roll, a shaft across said ¹³⁰

- frame, rock arms resiliently mounted on said shaft, journals for said roll in said rock arms, means for swinging said shaft to carry the roll away from the platen, a deflector comprising ears embracing said shaft, and means mounted on said arms to resiliently hold said deflector aligned upon the shaft and permit it to swing on said ears to move to and from the platen with the roll when 10 said platen is shifted in said frame.
11. In a front-strike typewriting machine, the combination with a platen and a platen frame, of a rear feed roll, a shaft, swinging arms upon which said shaft is mounted, rock 15 arms journaled upon said shaft and comprising bearings for said roll, springs effective on said rock arms to hold the roll against the platen, means for moving the platen rearwardly, and a connection from the 20 platen to said swinging arms.
12. In a front-strike typewriting machine, the combination with a platen and a platen frame having ends, of a rear feed roll, a shaft, swinging arms upon which said shaft 25 is mounted, rock arms journaled upon said shaft and comprising bearings for said roll, springs effective on said rock arms to hold the roll against the platen, means for moving the platen rearwardly, an axle for the 30 platen moving in slots in said ends, and a link journaled on each end of the platen axle and connected to said swinging arms.
13. In a front-strike typewriting machine, the combination with a platen and a platen 35 frame having ends, of an axle for the platen extending through slots in said ends, swinging arms comprising journals for the platen, a rear feed roll, swinging arms carrying said roll, and links connecting the two sets 40 of swinging arms.
14. In a front-strike typewriting machine, the combination with a platen and a platen frame having ends, of an axle for the platen extending through slots in said ends, swinging arms comprising journals for the platen, a rear feed roll, swinging arms carrying 45 said roll, links connecting the two sets of swinging arms, and a deflector connected to move with said roll.
15. In a front-strike typewriting machine, the combination with a platen and a platen 50 frame having ends, of an axle for the platen extending through slots in said ends, swinging arms comprising journals for the platen, a rear feed roll, swinging arms carrying said roll, links connecting the two sets of 55 swinging arms, a front roll from which the platen so moves, a finger-piece for moving said platen to insert a thick pack of sheets, and a separate finger-piece for moving said platen 60 a less distance and adapted to hold it there.
16. In a front-strike typewriting machine, the combination with a revoluble platen, and front and rear feed-rolls, of means for 65 moving the platen rearwardly, connections for automatically moving said rear roll at the same time, and a finger-piece adapted to move the platen a less distance from said front rolls and hold it at said distance.
17. In a front-strike typewriting machine, 70 the combination with a platen and a platen frame having ends, of an axle for the platen, arms swinging in said ends, and having journals for the axle, a rock-shaft journaled in said ends, rock arms pivoted to said swing- 75 ing arms and adapted to be swung with the shaft to withdraw the platen, a finger-piece adapted to swing one rock arm a substantial distance and hold it swung, a second finger-piece adapted to swing the other rock arm a 80 less distance and hold it swung, and feed-rolls against which the platen normally bears and from which it is swung.
18. In a front strike type-writing machine, the combination with a platen and a platen 85 frame having ends, of an axle for the platen, arms swinging in said ends and having journals for the axle, a rock-shaft journaled in said ends, rock arms pivoted to said swinging arms and adapted to be swung 90 with the shaft to withdraw the platen, a finger-piece adapted to swing one rock arm a substantial distance and hold it swung, a second finger-piece adapted to swing the other rock arm a less distance and hold it 95 swung, feed-rolls against which the platen normally bears and from which it is swung, and another feed-roll adapted to be swung with the platen.
19. In a front-strike typewriting machine, 100 the combination with a revoluble platen having front and rear feed-rolls cooperating therewith, of means for moving said platen rearwardly, a second means for moving the platen rearwardly a less distance, and automatic means for moving said front and 105 rear feed-rolls away from the platen when said first-mentioned means is operated, said front feed-rolls alone being adapted to move away from the platen when said second 110 means is operated.
20. In a front-strike typewriting machine, the combination with a revoluble platen, of a paper-table adapted to deliver 115 work-sheets thereto from the rear, said paper-table being adapted to detain a work-sheet lying upon the platen while a second work-sheet is adjusted outside the first, a collating table above the platen upon which the second work-sheet may be adjusted, and 120 a finger below said table adapted to assist in detaining the inside work-sheet.
21. In a front-strike typewriting machine, the combination with a revoluble platen, of a paper-table adapted to deliver 125 work-sheets thereto from the rear, feed-rolls, and means for effecting separation between the platen and the feed-rolls to enable work-sheets to be inserted therebetween, said platen being adapted to be automatically 130

made effective at said separation to hold an inside work-sheet upon the platen while the first-named sheets are being inserted.

22. In a front-strike typewriting machine, the combination with a revoluble platen, of a paper-table adapted to deliver work-sheets thereto from the rear, feed-rolls, means for effecting separation between the platen and the feed-rolls to enable work-sheets to be inserted therebetween, said platen being adapted to be automatically made effective at said separation to hold an inside work-sheet upon the platen while the first named sheets are being inserted, and a finger above the printing point adapted to detain the inside sheet at the front of the platen.

23. In a front-strike typewriting machine, the combination with a revoluble platen and a paper-table adapted to deliver work-sheets thereto from the rear, of a second paper-table adapted to receive sheets inserted from the rear and to guide them outside the first table, feed-rolls, and means for effecting separation of the platen and feed-rolls to enable the outside sheets to be inserted, said platen being adapted for holding an inside work-sheet to the platen when the separation is effected.

30 24. In a front-strike typewriting machine, the combination with a revoluble platen and a paper-table adapted to deliver work-sheets thereto from the rear, of a second paper-table adapted to receive sheets inserted from the rear and to guide them outside the first table, feed-rolls, and means for effecting separation of the platen and feed-rolls to enable outside sheets to be inserted and to clamp said first paper-table 40 against the platen to hold an inside work-sheet against shifting.

25. In a front-strike typewriting machine, the combination with a revoluble platen, of a paper apron in front of and below the platen to guide a front inserted work-sheet rearwardly, a rear paper table to enable the insertion of a work-sheet from the rear, feed-rolls including a rear feed-roll normally bearing against the platen, 50 means for effecting separation between the platen and the feed-rolls to enable the work-sheets to be inserted at the front, and normally ineffective means for holding an inside work-sheet but adapted to be made effective by said separation.

26. In a front-strike typewriting machine, the combination with a revoluble platen, of a paper apron in front of and below the platen to guide a front inserted work-sheet 60 rearwardly, a rear paper-table to enable the insertion of a work-sheet from the rear, feed-rolls including a rear feed-roll normally bearing against the platen, and means for effecting separation between the platen 65 and the feed-rolls to enable the work-sheets

to be inserted at the front, said rear paper-table being adapted to be moved against the platen by said separation to clamp an inside work-sheet against the platen.

27. In a front-strike typewriting machine, 70 the combination with a platen, of a rear paper-table, said paper-table being adapted to hold an inside work-sheet against the platen while an outside work-sheet is being inserted.

28. In a front-strike typewriting machine, the combination with a platen, of a rear paper-table, said paper-table being adapted to hold an inside work-sheet against the platen while an outside work-sheet is being 80 inserted, and fingers at the front of the platen adapted to assist in holding the inside sheet.

29. In a front-strike typewriting machine, 85 in combination, a revoluble platen, a curved paper-apron having its front edge adjacent the platen below the printing point and its rear edge spaced from the bottom of the platen at the rear of the vertical plane passing through the axis of the platen, feed-rolls to co-operate with the platen at the forward edge of said paper-apron, record-sheet-controlling means including a downwardly-inclined rear paper-table having its 90 lower edge spaced from the back of the platen, and a deflector to guide a record-sheet from the lower edge of said rear paper-table to the back of the platen and down around the same to engage the paper-apron, a bottom paper-table to direct work-sheets 100 inserted at the rear between the rear edge of the paper-apron and the platen, and means to shift the platen upwardly and rearwardly from the paper-apron and feed-rolls and into engagement with said rear paper-table, thereby clamping the record-sheet 105 against movement and providing ample space between the platen and both the paper-apron and feed-rolls for work-sheets introduced around the platen outside of the 110 record-sheet.

30. In a front-strike typewriting machine, 115 in combination, a revoluble platen, a curved paper-apron having its front edge adjacent the platen below the printing point and its rear edge spaced from the bottom of the platen at the rear of the vertical plane passing through the axis of the platen, feed-rolls to co-operate with the platen at the forward edge of said paper-apron, record-sheet-controlling means including a downwardly-inclined rear paper-table having its lower edge spaced from the back of the platen, and a deflector to guide a record-sheet from the lower edge of said rear paper-table to the back of the platen and down around the same to engage the paper-apron, a bottom paper-table to direct work-sheets inserted at the rear between the rear edge of the paper-apron and the platen, means to shift the 120 125 130

platen upwardly and rearwardly from the paper-apron and feed-rolls and into engagement with said rear paper-table, thereby clamping the record-sheet against movement 5 and providing ample space between the platen and both the paper-apron and feed-rolls for work-sheets introduced around the platen outside of the record-sheet, and means whereby actuation of the platen- 10 shifting means will effect a shifting of the deflector away from the platen.

31. In a front-strike typewriting machine, in combination, a revoluble platen, a curved paper-apron having its front edge adjacent 15 the platen below the printing point and its rear edge spaced from the bottom of the platen at the rear of the vertical plane passing through the axis of the platen, feed-rolls to co-operate with the platen at the forward edge of said paper-apron, record-sheet-controlling means including a downwardly-inclined rear paper-table having its lower edge spaced from the back of the platen, a deflector to guide a record-sheet 20 from the lower edge of said rear paper-table to the back of the platen and down around the same to engage the paper-apron, and a feed-roll adjacent to said deflector to co-operate with the platen to feed the record-sheet between the platen and deflector, a bottom paper-table to direct work-sheets inserted at the rear between the rear edge of the paper-apron and the platen, and means to shift the platen upwardly and rearwardly from the paper-apron and adjacent feed-rolls and into engagement with said rear paper-table, thereby clamping the record-sheet against movement and providing ample space between the platen and both the paper-apron and feed-rolls for work-sheets introduced around the platen outside of the record-sheet. 25

32. In a front-strike typewriting machine, in combination, a revoluble platen, a curved paper-apron having its front edge adjacent the platen below the printing point and its rear edge spaced from the bottom of the platen at the rear of the vertical plane passing through the axis of the platen, feed-rolls 30 to co-operate with the platen at the forward edge of said paper-apron, record-sheet-controlling means including a downwardly-inclined rear paper-table having its lower edge spaced from the back of the platen, a deflector to guide a record-sheet from the lower edge of said rear paper-table to the back of the platen and down around the same to engage the paper-apron, and a feed- 35

roll adjacent to said deflector to co-operate with the platen to feed the record-sheet between the platen and deflector, a bottom paper-table to direct work-sheets inserted at the rear between the rear edge of the paper-apron and the platen, and means to shift the platen upwardly and rearwardly from the paper-apron and adjacent feed-rolls and into engagement with said rear paper-table, thereby clamping the record-sheet against movement and providing ample space between the platen and both the paper-apron and feed-rolls for work-sheets introduced around the platen outside of the record-sheet. 40

33. In a front-strike typewriting machine, in combination, a revoluble platen, a paper-apron below said platen, the forward edge of the paper-apron being adjacent the lower front portion of the platen when the latter is in its normal position, and the rear edge of the paper-apron being spaced from the bottom of the platen to facilitate the insertion from the rear of the leading edges of work-sheets between the rear edge of the paper-apron and the platen, feed-rolls extending through openings in the forward portion of the paper-apron to co-operate with the platen in feeding work-sheets around the latter, a substantially horizontal bottom paper-table to direct work-sheets to the rear of the paper-apron, a forwardly and downwardly inclined upper paper-table having its lower edge in substantially the same horizontal plane as the axis of the platen and spaced to the rear of the platen when the latter is in its normal position, a deflector to guide a record-sheet inserted over the upper paper-table around the lower rear part of the platen to insure the passage of the record-sheet to the paper-apron, and a feed-roll to co-operate with the platen adjacent said deflector, means to shift the platen upwardly and rearwardly away from the paper-apron and the feed-rolls extending therethrough to facilitate the insertion of work-sheets outside of the record-sheet, and means operable by said platen-shifting means to move said deflector away from the platen. 45
